INERTIA OPERATING MEMBER FOR
AUTOMATIC FIREARMSJohn L. Lochhead, Springfield, Mass., assignor to
Olin Industries, Inc., New Haven, Conn., a cor-
poration of Delaware

Application November 21, 1946, Serial No. 711,242

9 Claims. (Cl. 89—182)

1

The present invention relates in general to firearms and more especially to a semi-automatic or fully automatic firearm having a fixed barrel and recoil-actuated mechanism for operating the breechblock.

An object of the invention is to provide an automatic firearm having a fixed barrel with improved mechanical means, as distinguished from gas-operated means, responsive to the recoil action of the firearm when fired, to automatically actuate the breechblock operating-mechanism.

A further object of the invention is to provide an automatic firearm having a fixed barrel with improved recoil-actuated breechblock operating-mechanism mounted in a compact manner within the forestock of the firearm.

A further object of the invention is to provide an improved automatic firearm having a fixed barrel in which the breechblock is automatically operated by recoil-actuated mechanism which is of relatively-simple construction, wholly mechanical in nature and of relatively few parts, all of which are sturdy and offer high resistance to wear.

A still further object of the invention is to provide an automatic firearm having a fixed barrel with an inertia-weight for operating the breechblock, the inertia-weight being adapted to use the initial recoil force of the firearm when fired to hold the breechblock in locked position and after the force of the recoil has spent itself to unlock the breechblock and move it rearwardly in the receiver.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a side elevation partly in section of the improved firearm of this invention, the breechblock being in its breech-closing position;

Fig. 2 is a side elevation of the firearm similar to Fig. 1 but immediately after the gun has been discharged, showing the displacement of the gun rearwardly with respect to the inertia-block of the breechblock actuating-mechanism;

Fig. 3 is similar to Fig. 1 except the action is

2

now open, the breechblock having been moved to its rearmost position in the receiver by the rearward movement of the inertia-block;

Fig. 4 is a sectional elevation on line 4—4 of Fig. 1;

Fig. 5 is a sectional elevation on line 5—5 of Fig. 1;

Fig. 6 is a perspective view of the inertia-block and the breechblock actuating-slides connected thereto; and

Fig. 7 is a perspective view of the breechblock.

Referring to the drawings, the particular firearm herein chosen for illustrating the invention is indicated generally at 10 and comprises a receiver 11 which is substantially U-shaped in cross section and comprises a top wall 12, spaced parallel side walls 13 and a front end-wall 14. The wall 14 is shown provided with two vertically-superposed apertures 15 and 16 to accommodate the rear ends respectively of the barrel 17 and tubular magazine 18, the latter being secured in its aperture 16 by a threaded connection. The rear end of the barrel 17 has a free fit in its aperture 15 of the front wall 14 of the receiver and embodies a substantially U-shaped barrel-extension 19 which extends rearwardly into a correspondingly-shaped relief-recess 20 formed in the underside and inner walls respectively of the top 12 and sides 13 of the receiver; the rear end of the barrel-extension 19 being adapted to be held securely in abutting engagement with a substantially-square shoulder 21 of the relief-recess 20 by means of the takedown-screw hereinafter described. The top wall of the barrel-extension 19 is provided with a longitudinally-extending substantially-rectangular slot 22, the rear end of which is provided with a beveled shoulder 23, as shown in Fig. 1, adapted to be engaged by a locking-lug 24 on the breechblock 25 to lock the latter in breech-closing position, as hereinafter described. As shown in Fig. 4, a longitudinal slot 26 is provided in one side of the barrel-extension coincident with an ejection-port 27 formed in one side 13 of the receiver for permitting fired cartridges to be ejected from the receiver. The bottom of the receiver 11 is an open slot which is adapted to be partially closed in a conventional manner by a trigger-plate indicated generally at 28 in which is mounted the trigger 29 and related

firing mechanism (not shown) for firing a car-

tride. The usual opening in the bottom of the receiver forwardly of the end of the trigger-plate is left to permit the cartridges to be loaded into the rear end of the tubular magazine 18. The bottom of the receiver 11 is also provided with a rearwardly-projecting tongue 30 having an internally-threaded aperture to receive the threaded end of a stud 31 of a stock-screw 32, the stud 31 and screw 32 being mounted in a longitudinal aperture of the stock 33 and arranged in the usual manner to secure the latter firmly to the rear end of the receiver. The stock 33 is also provided with a second longitudinal aperture 34 which is adapted to accommodate an action-closing spring 35, the rear end of which seats against the bottom of the aperture 34. The forward end of the action-closing spring carries a spring-pilot 36 which is slidably mounted in the forward end of a guide-tube 37, the latter being, in turn, secured in the open end of the stock-aperture 34. The front face of the spring-pilot 36 comprises a shallow concave recess in which the rounded rear-end of an action-link 38 is adapted to seat, the forward end of the link 38 being pivotally connected to the breechblock 25, as described below.

The breechblock is a substantially-solid rectangular block, the top of which has a radius corresponding substantially to the radius of the top wall of the barrel-extension and embodies the usual firing-pin 39 and extractor- and ejector-members (not shown). The breechblock is arranged in a conventional manner to reciprocate longitudinally in the receiver and to have pivotal movement therein in the vertical plane thereof at both the forward and rearward extremities of its excursion, its pivotal movement at the forward end of the receiver being adapted to engage and disengage the locking-lug 24 of the breechblock with the beveled shoulder 23 of the fixed barrel-extension for locking and unlocking the breechblock in and from breech-closing position respectively, in the manner well known in the art.

Referring to Figs. 4 and 7, a clearance-notch is provided on the underside of the breechblock and forms spaced parallel flanges on opposite sides thereof as indicated generally at 41, their lower edges 43 being adapted, as hereinafter described, to cooperate with suitable slide-action mechanism to hold the breechblock in breech-closing position immediately following the firing of a cartridge so as to provide for a delayed action in opening the breech. The edges 43 of the flanges 41 terminate in the forward edges 44 of a cam-slot 45 which comprises the aforesaid pair of spaced parallel front edges 44 and a pair of spaced parallel rear edges 46 in parallel relationship thereto, the cam-slot 45 extending rearwardly and upwardly in a depending-lobe 47 formed at the rear end of each flange 41.

The action of the breechblock is controlled in general by engagement of a transverse action-pin 48 in the cam-slot 45 and with the edges 43 of the breechblock. To this end, a pair of action-bars 49 are slidably mounted in suitable guide-slots 50 in the front wall 14 and side walls 13 of the receiver, the bars 49 being adapted to extend rearwardly into the receiver on opposite sides respectively of the breechblock. Each end of the action-pin 48 has a drive fit in a corresponding aperture in the rear end of its respective action-bar 49, as shown clearly in Fig. 6, and is adapted, in its normal position, that is to say, when the breechblock is in breech-closing position prior to firing a cartridge, to engage the edges 43 of the breechblock adja-

cent the rear extremities thereof, as shown in Fig. 1, the action-pin 48 serving thus to prevent pivotal displacement of the breechblock out of breech-closing position.

Referring to Fig. 1, the transverse action-pin 48 also constitutes the means for pivotally connecting the forward end or wrist 51 of the action-link 38 to the breechblock, the wrist 51 being located in the aforesaid clearance-notch in the underside of the breechblock and designed to make a nice fit between the spaced parallel flanges 41 thereof. Referring to Fig. 4, the flanges 41 of the breechblock and, in particular, the lobes 47 thereof, are shown to be accommodated in clearance-spaces formed between opposite sides of the link-wrist 51 and the corresponding rear ends of the respective slide-action bars, and in accordance with this construction the cam-surfaces 44 and 46 respectively of the cam-slot 45 are adapted to be operatively engaged by those portions of the action-pin 48 which extend across the aforesaid clearance-spaces.

When the breechblock is in its forward breech-closing position in the receiver, the lug 24 of the breechblock is adapted to lockingly engage the shoulder 23 of the fixed barrel-extension and is held in engagement therewith by engagement of the action-pin 48 with the edges 43 of the breechblock. The breechblock is adapted to be unlocked and moved rearwardly in the receiver by moving the action-pin 48 rearwardly relative to the breechblock, so as to displace the pin from the edges 43 into the cam-slot 45 and, in particular, into engagement with the rear edge 46 thereof, thereby pulling the rear end of the breechblock downwardly so as to disengage the lug 24 from the shoulder 23, whereupon the breechblock may be moved rearwardly in the receiver. During the rearward movement of the breechblock, the link 38 which connects the breechblock 25 to the closing-spring 35 compresses the latter, as indicated in Fig. 3. At the end of the rearward excursion of the breechblock, the action-pin 48 of the link 38 is biased to move forwardly, by the force of the compressed closing-spring 35, into engagement with the forward edge 44 of the cam-slot 45, as a consequence of which the breechblock is moved forwardly into breech-closing position.

The improved means of this invention for moving the action-pin 48 rearwardly to unlock the breechblock and initiate its rearward excursion, comprises recoil-actuated means, indicated generally at 52, consisting of an inertia-weight or -block 53 cooperatively associated with a recoil-unlocking spring 54, as hereinafter described. Referring to Fig. 6, the inertia-weight 53 comprises a longitudinal block substantially rectangular in cross section, the underside 55 of which is substantially semicylindrical in shape and concentric with the semicylindrical inside wall of the forestock 56. The upper surface of the inertia-block comprises a longitudinal, substantial-ly-semicylindrical recess 57 to provide clearance for the underside of the barrel 17, as shown in Fig. 5. Extending longitudinally through the inertia-block is a cylindrical aperture 58, the diameter of which may be slightly greater than the diameter of the tubular magazine 18, whereby the inertia-block may be mounted on the magazine and moved freely back and forth thereon. To this end, the forward end of the magazine is adapted to be supported in the axially-aligned aperture 59 of a depending barrel-lug 60 formed integrally or otherwise secured to the forward end of a barrel. The forward end of the maga-

zine has a free fit in the aperture 59 of the lug 60 and is adapted to be secured therein by a take-down screw 61. The latter comprises a threaded shank 62 adapted to be screwed into the forward end of the magazine; and a shoulder 63 arranged to be brought into abutting engagement with the front face of the barrel-lug 60 as the screw 61 is tightened. By tightening the take-down screw 61, the barrel-lug 60 and barrel 17 are forced rearwardly relative to the magazine 18 thereby forcing the end of the barrel-extension against the shoulder 21 of the relief-recess in the receiver to firmly secure the barrel therein. At the same time, the forward end of the magazine 18 is firmly secured in the aperture of the barrel-lug 60. It will be understood that by unscrewing the take-down screw 61 and moving the breech-block rearwardly out of locking engagement with the barrel-extension 19, the barrel may be readily withdrawn from the receiver.

It should be noted also that the forestock 56 is fixedly secured on the underside of the barrel by the take-down screw 61 which when tightened up is adapted to bind the opposite ends of the forestock between the forward face of the front wall 14 of the receiver and the rear face of the barrel-lug 60. Whenever the take-down screw is loosened, the forestock 56 may be readily removed.

Extending rearwardly from the front end of the tubular magazine and formed in the top wall thereof, is a substantially-rectangular relatively-narrow slot 64 which is slightly greater than one-third the over-all length of the tubular magazine and terminates in a transverse shoulder 65.

Referring again to Fig. 6, at the front end of the inertia-block is a longitudinal slot 66 which intersects the cylindrical aperture 58 and the semicylindrical recess 57 of the inertia-block and terminates in a transverse shoulder 67. The width of the slot 66 corresponds substantially to the width of the slot 64 of the tubular magazine and is about one-third its length, the two slots 64 and 66 respectively being arranged in the same vertical plane, as shown in Fig. 5. Suitably secured to the rear end of the inertia-block and on opposite sides thereof adjacent its top edges, are the forward ends of the slide-action bars, each of which extends rearwardly on opposite sides of the tubular magazine within the encompass of the fixed forestock 56. The tubular magazine is provided adjacent its forward end with a plug 68 which is secured by a pin 69 in the magazine adjacent the transverse shoulder 65 thereof. The plug 68 constitutes a stop for the forward end of the magazine-spring 70, the rear end of which is accommodated in the usual manner in an apertured magazine-follower 71, the latter being adapted to move cartridges from the magazine rearwardly into the receiver from whence they are automatically loaded into the chamber of the barrel by conventional carrier-means (not shown) acting in conjunction with the forwardly-moving breechblock.

Supported in the forward end of the tubular magazine is the recoil-unlocking spring 54, the forward end of which engages the takedown-screw 61. The rear end of the recoil-unlocking spring is received in the longitudinal aperture of a pilot-member 72 which is slidably mounted in the forward end of the tubular magazine and has a guide-finger 73 which is arranged to extend upwardly through the slots 64 and 66 of the tubular magazine and the inertia-block respectively and to be urged normally by the force of the recoil-

unlocking spring 54 into engagement with the transverse shoulders 65 and 67 thereof.

The entire assembly, including the tubular magazine, the inertia-block and the recoil-unlocking spring, is adapted to be enclosed within the forestock 56 of the firearm, the stock being suitably secured to the magazine in any conventional manner.

In order to initially load the firearm, it is proposed to provide a manually-operable handle 74 for opening the breech and loading a cartridge into the chamber of the barrel. Referring to Fig. 6, the handle 74 is arranged to be secured to one of the slide-action bars 49 and to project outwardly through a longitudinal slot 75 in the adjacent side 13 of the receiver. By grasping the handle 74 and pulling it rearwardly, the firearm may be loaded, preparatory to firing the first cartridge, following which the firearm automatically ejects the fired cartridge and reloads, as described below.

The operation of the firearm may be described briefly as follows: With the breechblock 25 in its forward breech-closing position, hereinabove referred to as its "normal" position, as shown in Fig. 1, its locking-lug 24 is in locking engagement with the shoulder 23 of the fixed barrel-extension 19, having been raised into locking engagement therewith by the force of the closing-spring 35 acting on the action-link 38. The transverse action-pin 48 is shown engaged on the edges 43 on the underside of the breechblock adjacent the rear ends thereof. With the parts in this relationship, the forward end of the inertia-block is in engagement with the upwardly-extending guide-finger 73 of the spring-pilot member 72, the latter being fixedly held against the transverse shoulder 65 of the magazine slot by the force of the recoil-unlocking spring 54. When the gun is discharged, the force of its recoil moves the gun, including the barrel, receiver, magazine, and recoil-unlocking spring and breechblock assembly, rearwardly with respect to the inertia-block and its attached action-bars 49, the inertia-block remaining substantially immobile and in continuous engagement with the finger 73 of the recoil-spring pilot 72. As a consequence of this action, the recoil-unlocking spring 54 is compressed, due to the relative movement of the spring 54 and inertia-block. Since the transverse action-pin 48 is secured to the rear ends of the slide-action bars 49 of the immobile inertia-block 53, the pin is moved forwardly, relatively speaking, in continuous engagement with the edges 43 of the breechblock, thereby positively holding the breechblock in breech-closing position immediately following the firing of the cartridge. After the force of the recoil has spent itself, the force of the compressed recoil-unlocking spring 54, acting on the spring-pilot member 72, thereupon drives the inertia-block 53 rearwardly on the tubular magazine 18, the spring-pilot 72 bringing up against the transverse shoulder 65 of the slot 64 in the tubular magazine. The rearward movement of the inertia-block thus displaces the transverse action-pin 48 of the slide-action bars rearwardly out of engagement with the edges 43 on the underside of the breechblock into the cam-slot 45 and particularly in camming engagement with the rear edge 46 thereof. Thereupon, the rearwardly-moving action-pin 48 forces the locking-lug 24 of the breechblock out of engagement with the shoulder 23 of the barrel-extension, and the continued rearward movement of the inertia-block carries the breechblock rearwardly in the

receiver to its rearmost position, as indicated in Fig. 3. During its rearward excursion, the link 38 of the breechblock compresses the closing-spring 35 in the stock 33, following which the breechblock is advanced to its forward position in the receiver by the force of the compressed closing-spring 35. During its forward movement, a cartridge which has been moved into the receiver from the magazine is lifted up into the path of the breechblock and engaged and moved thereby into the chamber of the barrel. Simultaneously, the slide-action bars 49 move the inertia-block 53 forwardly on the tubular magazine 18 until its forward end again engages the upwardly-projecting finger 73 of the recoil-spring pilot 72. The elements of the firearm are again in normal firing position.

Although the firearm structure, and in particular the recoil-actuated means described above for automatically operating the breechblock, is wholly successful, it is within the purview of the invention to provide for the nice balance of the firearm by proportioning the weight of the inertia-means between the inertia-block 53 in the forestock 56 and the spring-pilot 36 or equivalent member in the buttstock 33. It will be appreciated that these elements are cooperatively engaged during recoil and, hence, the effective weight of the inertia-means equals the combined weight of the spring-pilot 36 and the inertia-block 53. Consequently, by distributing this combined weight in the proper ratio as, for example, by modifying the inertia-block 53 and spring-pilot 36 of the present embodiment so that the two are of substantially equal weight, any tendency for the firearm to be "muzzle heavy" or to have a heavy buttstock may be successfully obviated, thus insuring a nicely balanced firearm.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In an automatic firearm: a receiver; a barrel secured to said receiver; a breechblock in said receiver movable into and out of locked position therein; and recoil-energized means to move said breechblock comprising an energy-storing member and an inertia-member connected therewith, said inertia-member having an element in slidable engagement with said breechblock and movable forwardly relative to said breechblock to hold said breechblock locked in breech-closing position immediately following the firing of a cartridge and simultaneously to store energy in said energy-storing member, said energy-storing member being arranged thereafter to move said inertia-member and said element rearwardly relative to said breechblock so as to unlock said breechblock and move it rearwardly in said receiver out of breech-closing position.

2. In an automatic firearm: a receiver; a barrel secured to said receiver; a breechblock in said receiver movable into and out of locked position therein; recoil-energized means to move said breechblock comprising an energy-storing member and an inertia-member connected therewith, said inertia-member having an element in slidable engagement with said breechblock and movable forwardly relative to said breechblock to hold said

breechblock locked in breech-closing position immediately following the firing of a cartridge and simultaneously to store energy in said energy-storing member, said energy-storing member being arranged thereafter to move said inertia-member and said element rearwardly relative to said breechblock and move it rearwardly in said receiver out of breech-closing position; and yieldable-means connected with said inertia-member and independent of said energy-storing member to restore said breechblock to breech-closing position.

3. In an automatic firearm: a receiver; a barrel secured to said receiver; a breechblock in said receiver movable into and out of locked position therein; recoil-energized means to move said breechblock comprising an energy-storing spring, and an inertia-block connected therewith, said inertia-block having an element in slidable engagement with said breechblock and adapted to remain substantially immobile relative to said breechblock on firing a cartridge so as to hold said breechblock locked in breech-closing position immediately thereafter and simultaneously to store energy in said energy-storing spring, said energy-storing spring being arranged subsequently to transmit its stored energy to said inertia-block thereby to move said inertia-block and its element rearwardly relative to said breechblock so as to unlock said breechblock and move it out of breech-closing position; and yieldable-means connected with said inertia-block and independent of said energy-storing spring to restore said breechblock to breech-closing position.

4. In an automatic firearm: a receiver; a barrel secured to said receiver; a breechblock in said receiver movable into and out of locked position therein; recoil-energized means to move said breechblock comprising an energy-storing spring, and an inertia-block connected therewith, said inertia-block having an element in slidable engagement with said breechblock and adapted to remain substantially immobile relative to said breechblock on firing a cartridge so as to hold said breechblock locked in breech-closing position immediately thereafter and simultaneously to store energy in said energy-storing spring, said energy-storing spring being arranged subsequently to transmit its stored energy to said inertia-block thereby to move said inertia-block and its element rearwardly relative to said breechblock so as to unlock said breechblock and move it out of breech-closing position; and stop-means arranged to be engaged by said energy-storing spring following the transmission of its energy to said inertia-block to disengage said energy-storing spring from said rearwardly moving inertia-block.

5. In an automatic firearm: a receiver; a barrel secured to said receiver; a breechblock in said receiver movable into and out of locked position therein; recoil-energized means to move said breechblock out of breech-closing position comprising a breechblock-actuating slide having a breechblock-contacting pin slidable forwardly and rearwardly relative to said breechblock, an energy-storing spring, and an inertia-block connected to said breechblock-actuating slide and said energy-storing spring, said inertia-block, actuating-slide and breechblock-contacting pin being adapted to remain substantially immobile relative to said breechblock on firing a cartridge so as to hold said breechblock locked in breech-closing position immediately thereafter and simultaneously to store energy in said energy-

storing spring, said energy-storing spring being arranged subsequently to transmit its stored energy to said inertia-block thereby to move said inertia-block, said breechblock-actuating slide and said breechblock-contacting pin rearwardly relative to said breechblock so as to unlock said breechblock and move it out of breech-closing position; stop-means arranged to be engaged by said energy-storing spring following the transmission of its energy to said inertia-block to disengage said energy-storing spring from said rearwardly-moving inertia-block; and spring-loaded means in engagement with said breechblock-actuating slide to operate said breechblock-actuating slide so as to restore said breechblock to breech-closing position and return said inertia-block into cooperative engagement with said energy-storing means.

6. In an automatic firearm: a receiver; a stock secured to one end of said receiver; a barrel secured to the opposite end of said receiver; a breechblock in said receiver movable into and out of locked position therein; a breechblock-actuating slide having a breechblock-contacting pin slidable forwardly and rearwardly relative to said breechblock; yieldable-means mounted in said stock arranged to engage the corresponding end of said breechblock-actuating slide normally to move said breechblock forwardly into breech-closing position; and recoil-energized means to unlock and move said breechblock out of breech-closing position comprising an energy-storing spring fixedly supported on the underside of said barrel adjacent the forward end thereof, and an inertia-block slidably supported on the underside of said barrel and connected at its rear end to said breechblock-actuating slide and at its opposite end with said energy-storing spring, said inertia-block, actuating-slide and breechblock-contacting pin being arranged to remain substantially immobile relative to said breechblock on firing a cartridge so as to hold said breechblock locked in breech-closing position immediately thereafter and simultaneously to store energy in said energy-storing spring, said energy-storing spring being arranged subsequently to drive said inertia-block, said breechblock-actuating slide and said breechblock-contacting pin rearwardly relative to said breechblock so as to unlock said breechblock and move it out of breech-closing position, said rearwardly-moving inertia-block and slide being adapted to store energy in said yieldable-means whereby the latter is energized to return said breechblock to breech-closing position.

7. In an automatic firearm: a receiver; a stock secured to one end of said receiver; a barrel secured to the opposite end of said receiver; a breechblock in said receiver movable into and out of locked position therein; a breechblock-actuating slide having a breechblock-contacting pin slidable forwardly and rearwardly relative to said breechblock; yieldable-means mounted in said stock arranged to engage the corresponding end of said breechblock-actuating slide normally to move said breechblock forwardly into breech-closing position; recoil-energized means to unlock and move said breechblock out of breech-closing position comprising an energy-storing spring fixedly supported on the underside of said barrel adjacent the forward end thereof, and an inertia-block slidably supported on the underside of said barrel, and connected at its rear end to said breechblock-actuating slide and at its opposite end with said energy-storing spring, said

inertia-block, actuating-slide and breechblock-contacting pin being arranged to remain substantially immobile relative to said breechblock on firing a cartridge so as to hold said breechblock locked in breech-closing position immediately thereafter and simultaneously to store energy in said energy-storing spring, said energy-storing spring being arranged subsequently to drive said inertia-block, said breechblock-actuating slide and said breechblock-contacting pin rearwardly relative to said breechblock so as to unlock said breechblock and move it out of breech-closing position; and stop-means arranged to be engaged by said energy-storing spring following the transmission of its energy to said inertia-block to disengage said energy-storing spring from said rearwardly-moving inertia-block, said rearwardly-moving inertia-block and slide being adapted to store energy in said yieldable-means whereby the latter is energized to return said breechblock to breech-closing position.

8. In an automatic firearm: a receiver; a barrel secured to said receiver; a tubular magazine supported on the underside of said barrel; a breechblock in said receiver movable into and out of locked position therein; recoil-energized means to move said breechblock comprising an energy-storing spring secured in the outer end of said tubular magazine, a spring-pilot in engagement with said energy-storing spring and slidably mounted in said tubular magazine and an inertia-block slidably supported on said tubular magazine said inertia-block having a breechblock-contacting pin at one end in slidable engagement with said breechblock, the opposite end of the latter being engaged with the pilot of said energy-storing spring, said inertia-block and said contacting-pin being arranged to remain substantially immobile relative to said breechblock on firing a cartridge so as to hold said breechblock locked in breech-closing position immediately thereafter and simultaneously move said spring-pilot forwardly relative to said energy-storing spring so as to compress said energy-storing spring, said compressed energy-storing spring being arranged thereafter to drive said spring-pilot, said inertia-block and said contacting-pin rearwardly thereby to unlock said breechblock and move it rearwardly out of breech-closing position; and yieldable-means cooperatively associated with said breechblock to restore said breechblock to breech-closing position.

9. In an automatic firearm: a receiver; a barrel secured to said receiver; a tubular magazine supported on the underside of said barrel; a breechblock in said receiver movable into and out of locked position therein; recoil-energized means to move said breechblock comprising an energy-storing spring secured in the outer end of said tubular magazine, a spring-pilot in engagement with said energy-storing spring and slidably mounted in said tubular magazine and an inertia-block slidably supported on said tubular magazine said inertia-block having a breechblock-contacting pin at one end in slidable engagement with said breechblock, the opposite end of the latter being engaged with the pilot of said energy-storing spring, said inertia-block and said contacting-pin being arranged to remain substantially immobile relative to said breechblock on firing a cartridge so as to hold said breechblock locked in breech-closing position immediately thereafter and simultaneously move said spring-pilot forwardly relative to said

energy-storing spring so as to compress said energy-storing spring, said compressed energy-storing spring being arranged thereafter to drive said spring-pilot, said inertia-block and said contacting-pin rearwardly thereby to unlock said breechblock and move it rearwardly out of breech-closing position; stop-means in said tubular magazine arranged to stop the rearward movement of said pilot thereby to disengage the spring-loaded pilot from said inertia-block; and spring-loaded means in engagement with said breechblock arranged to restore said breechblock to breech-closing position and to return said in-

ertia-block into engagement with said spring-pilot.

JOHN L. LOCHHEAD.
